Ino. T. Davy's
Design for Parlor Grate.

Patented Dec. 23. 1856.

1

Dec. 855

John V. Davy, of Troy, N.Y.
Letters Patent No 855 Dated Dec 25th 1836

The Schedule referred to in these Letters Patent and
making part of the same.

To all whom it may concern:

Be it known that I,
John V. Davy of Troy in the county of Rensselaer
and State of New York, have invented or produced
a new and original design for a parlor stove grate,
and I do hereby declare that the following is a
full, clear and exact description of the same, ref-
erence being had to the annexed perspective draw-
ing, and to the letters of reference marked thereon,

2

Des. 855

forming part of this specification.

My design for parlor stove grate, is as follows viz. A is the top plate, decorated with the ornamental center (a) and cover (b). B is the front plate decorated with the scroll sides (c c c c) and letters (d d). (g, g) are ornamental sunk panels, (h) is an ornamental key of the grate arch, (i) is an ornamental moulding around the grate arch, C is the blower plate, with the ornamental devices (j j) arranged upon its surface, D is the centre plate, E is the damper plate, with the ornamental moulding (k), F is the bottom plate, decorated with the ornamental border moulding (l l) and the leaves (m, m) at the angles and ends of the mouldings, G is the leg with the ornamental devices (n) upon its face.

Having fully described my design for parlor stove grate, What I claim as new and desire to secure by letters patent, is. The ornamental configuration and design for a parlor stove grate, such as herein described, and shown in the annexed perspective drawing.
